Primary Examiner — Susan Bennett Hattan*Assistant Examiner* — Lauren D McVey(74) *Attorney, Agent, or Firm* — Design IP(57) **CLAIM**

The ornamental design for a support apparatus, as shown and described.

DESCRIPTION

FIG. 1 is a perspective view of a support apparatus showing our new design;

FIG. 2 is a front view thereof;

FIG. 3 is a rear view thereof;

FIG. 4 is a left side view thereof;

FIG. 5 is a right side view thereof; and,

FIG. 6 is a top view thereof.

The broken lines shown illustrate portions of the support apparatus that form no part of the claimed design.

1 Claim, 6 Drawing Sheets(56)
